UNITED STATES PATENT OFFICE.

GEORGE BULLOCK AND ARTHUR E. TEMPLEMAN, OF GRAND JUNCTION, COLORADO.

ELECTRIC IRON.

1,282,039.

Specification of Letters Patent.

Patented Oct. 22, 1918.

Application filed December 8, 1917. Serial No. 206,147.

To all whom it may concern:

Be it known that we, GEORGE BULLOCK and ARTHUR E. TEMPLEMAN, citizens of the United States, residing at the city of Grand Junction, county of Mesa, and State of Colorado, have invented a new and useful Electric Iron, of which the following is a specification.

This invention relates to electric irons.

10 An object of the invention is to provide a device adapted to be connected with an electric iron for supporting the cord or wires to which the iron is connected in order to support the same out of the way so that the 15 iron may be operated without obstruction thereby, and means for preventing displacement of said device during the operation of the iron.

Another object of the invention is to provide 20 a device of the character mentioned adapted to be removably connected to the iron, for supporting the cord out of the way during the operation of the iron, and a removable means for locking said device in 25 position to prevent displacement thereof while the iron is being operated.

Another object is to provide an improved 30 connection for the electric cord mechanism of the iron, and means for supporting the cord out of the way when the iron is in operation.

Other objects will appear from the following description, reference being made to the accompanying drawings in which we have 35 illustrated one form of the invention, and in which—

Figure 1 is a side elevation of an electric iron embodying our invention, the handle of the iron being in section.

40 Fig. 2 is an elevation of the device in connection with the iron looking toward one end of the iron.

Fig. 3 is a view illustrating the clasp by which the cord is supported.

45 The electric iron illustrated in Figs. 1 and 2 is of a well known type having a support 1 in connection therewith for supporting the handle.

In the embodiment illustrated the handle 50 2 is carried by the support 1 at a desired height above the iron. At one end of the iron the electric connections 3 are secured from which an insulating cord 4 extends into the tube 5 on which the handle is mounted.

55 A cord 6 incloses the electric wires which are connected with a plug 7 having contact

points 8 in circuit with the wires in the cord. The plug 7 is adapted to be removably inserted in the open end of the tube 5 so that the contact points 8 will contact with the 60 wires in the cord 4 and thereby supply the necessary electric current to the iron to heat the same. While the iron illustrated embodies the construction just described it will be perfectly apparent that other features of 65 the invention may be used in connection with said construction or independently thereof as desired; and it will also be apparent that when used in connection with the construction described there is direct coöperation 70 between the parts of the invention.

Another feature of our invention consists of a support adapted to be engaged with the iron structure or with the handle to support the wires or cord out of the way so that the 75 iron may be operated without inconvenience therefrom. The device may be composed of any suitable or appropriate material and, although we have illustrated the device composed of sheet metal, it will be readily 80 understood that it may be otherwise constructed and still remain within the scope of the invention.

In the embodiment illustrated the support is composed of sheet metal which is preferably 85 shaped to form a supporting arm 9 adapted to extend upwardly from the iron outside of the vertical plane of the handle as will be readily understood by reference to Fig. 1. The side edges of the supporting 90 arm 9 are preferably curved and the upper extremity of said arm has two projections arranged to receive and retain the cord or wires between them. As shown, the two projections include converging portions 10 and 95 outwardly diverging portions 11, the latter forming a guide by which the cord is guided when being pressed between the projections into the clamping portion thereof. The application of the cord will be readily understood 100 by reference to Fig. 1 in which it will be seen that the cord is embraced and held between the projections which constitute a species of clamp for removably holding the cord with sufficient firmness to prevent slack 105 portions thereof from getting in the way of the iron when in operation.

The lower portion of the arm is provided with one or more holes 12 (two in the present instance) from each of which a slot 13 110 extends upwardly. An equal number of lugs or projections 14 are in connection with the

handle structure and are provided with flat vertical sides so that they may be received within the slots 13 and thus support the arm 9 in a vertical position. The lugs 14 are 5 formed with heads 15 which may pass through the holes 12 when the device is being applied to or removed from the iron, and after the heads have passed through said holes the arm is slipped downwardly until 10 the lugs or projections 14 are within the slots 13 and until one of the holes 12 is in alignment with the tube 5. Thus, when the plug 7 is connected to the iron it extends through the hole 12 and into the tube 5 to 15 complete the circuit and when so located the plug prevents the arm 9 from being raised or otherwise detached from the handle structure. Thus the arm 9 is located in position when the plug is in connection with the iron 20 structure.

From the foregoing it is apparent that we have provided a very convenient and highly useful attachment for electric irons to overcome a well recognized inconvenience hereinbefore encountered in the operation thereof.

We do not restrict ourselves in the construction of the supporting arm to sheet metal nor to other unessential details or features of construction. What we claim and 30 desire to secure by Letters Patent, is:—

1. The combination with the handle of an electric iron, of a support, one of said parts having openings therein, projections on the other one of said parts adapted to engage in 35 said openings and thereby uphold said support, and means in connection with said support for engaging the cord of the electric iron.

2. The combination with an electric iron, 40 an electric wire cord, and projections carried by the iron, of a support removably carried by said projections for supporting the cord out of the way during the operation of the iron, and means supported by the iron independently of said projections for locking 45 said support in position to prevent displacement thereof while the iron is being operated.

3. The combination with an electric iron, 50 an electric wire cord, and supporting projections carried by the iron, of a support removably carried by said projections for supporting the cord out of the way during the operation of the iron and having a hole 55 therethrough and a removable element carried by the iron independently of said projections and extending through said hole for locking said support in position to prevent displacement thereof while the iron is being 60 operated.

4. In an electric iron, a handle, and a cord 65 inclosing the wires by which the electric current is supplied to the iron, in combination with an upright arm removably carried by the handle and arranged to engage with the

cord to support the same out of the way during operation of the iron, and a removable device supported by the iron independently of said arm for preventing displacement of the arm. 70

5. In an electric iron, a handle, and a cord inclosing the wires by which the electric current is supplied to the iron, in combination with an arm, elements supported by the iron for supporting said arm in an 75 upright position, a device supported by the iron independently of said elements for preventing displacement of the arm, and means carried by said arm for engaging and supporting the electric wire cord and supporting the same out of the way during 80 operation of the iron.

6. In an electric iron having electric heating means, a handle for operating the iron, a projection on said handle, a head on said 85 projection, an arm having an opening through which said projection may pass and having a slot extending upwardly from said opening arranged to receive the projection and thereby support the arm, means for 90 engaging the arm with an electric wire cord, and means for preventing displacement of the arm.

7. In an electric iron having electric heating means, a handle for operating the iron, 95 a support secured to the iron for supporting the handle, a projection on said support, a head on said projection, an arm having an opening through which said head may pass and having a slot extending upwardly from 100 said opening for receiving said projection whereby said arm will be supported in an upright position, means for engaging said arm with the electric wire cord, and a device for preventing displacement of said 105 arm.

8. A device of the character described, comprising in combination with an electric iron, a handle, projections rigidly supported by the handle, an arm composed of sheet 110 metal having its side edges curved to render the arm arcuate in cross section, said arm having slots for receiving said projections, means for preventing said arm from being detached from said projections whereby the 115 arm will be supported in an upright position, and means in connection with said arm for engaging and supporting an electric wire cord.

9. A device of the character described comprising, in combination with an electric iron, a cord inclosing the wires by which the electric current is supplied to the iron, a handle, contact members within the handle, an arm, means for removably supporting 120 the arm in connection with the handle, a plug for locking the arm in connection with the handle, contact members on the plug to contact with the contact members in the handle to complete the electric circuit, and 125 130

means in connection with the arm for supporting the cord out of the way during operation of the iron.

10. A device of the character described comprising, in combination with an electric iron, a handle, contact members within the handle, an arm, means for removably supporting the arm in connection with the handle, a plug for locking the arm in connection with the handle, and contact members on the plug to contact with the contact members in the handle to complete the electric circuit.

11. A device of the character described, comprising an arm having longitudinal slots therein, an electric iron handle, pro-

jections on said handle arranged to engage within said slots and support said arm in an upright position, and means in connection with said arm for engaging an electric wire cord.

12. A device of the character described, comprising an arm having elongated slots therein, an electric iron handle, projections on said handle arranged to engage in said slots and support said arm in an upright position, means for locking said arm in connection with said projections, and means in connection with said arm for engaging an electric wire cord.

GEORGE BULLOCK.
ARTHUR E. TEMPLEMAN.
